(57) CLAIM

The ornamental design for an electronic sound book with microphone, as shown and described.

DESCRIPTION

The article in which the design is embodied is an electronic sound book having a microphone attached thereto.

FIG. 1 is a perspective view of an electronic sound book with microphone showing our new design;

FIG. 2 is a front elevational view thereof;

FIG. 3 is a bottom plan view thereof;

FIG. 4 is a top plan view thereof;

FIG. 5 is a right side elevational view thereof;

FIG. 6 is a left side elevational view thereof;

FIG. 7 is rear elevational view thereof; and,

FIG. 8 is a another perspective view similar to FIG. 1 but in which the microphone component is shown stored in the recessed holding compartment of the book.

The surface(s) or portion(s) of the article not shown in the drawing or described in the specification form(s) no part of the claimed design.
